UNITED STATES PATENT OFFICE.

HARRY W. JONES, OF BEDFORD, VIRGINIA, ASSIGNOR TO THE AMERICAN CAN COMPANY, OF NEW YORK, N. Y., A CORPORATION OF NEW JERSEY.

ART OF MAKING CONTAINERS.

Application filed March 15, 1919, Serial No. 282,849. Renewed December 9, 1922.

To all whom it may concern:

Be it known that I, HARRY W. JONES, a citizen of the United States, residing in Bedford, in the State of Virginia, have ⁵ invented a new and useful Improvement in the Art of Making Containers, of which the following is a specification.

This invention relates in general to the art of making containers and has more particular reference to the provision of containers having hinged flanged covers, and has for its object the provision of an improved process for making said containers together with apparatus for carrying out ¹⁰ said process.

My invention contemplates the provision of a box having a flanged hinged cover, the hinge being provided by completely first ¹⁵ positioning a hinged staple and then subsequently attaching the cover to it. This permits the use of the ordinary stapling machines in combination with apparatus for subsequently securing the attached cover in place and consequently the manufacture ²⁰ of the box at an extremely low cost while at the same time providing a greatly improved box. The process, the combination of instrumentalities used and the box itself are all believed new.

³⁰ The invention contemplates also the application of the label to the box before the hinge is positioned, and when the hinge and cover are applied the performance of this operation without marring the appearance ³⁵ of the label.

Numerous other objects and advantages of the invention will be apparent as it is better understood from the following description when considered in connection ⁴⁰ with the accompanying drawing illustrating the same.

On the drawing,

Figure 1 is a perspective view of parts of the box and apparatus showing their ⁴⁵ arrangement preparatory to the beginning of the assembling.

Fig. 2 is a similar view showing the arrangement of the parts in positioning the staple;

⁵⁰ Fig. 3 is a section showing the completion of the positioning of the staple;

Fig. 4 is a perspective view of an end of the box showing the arrangement of the staple when in place;

⁵⁵ Fig. 5 is a similar view showing the ini-

tial step in assembling the cover on the box; and

Figs. 6 and 7 show a means for bending the hinged tongue or cover lug about the ⁶⁰ staple.

Referring first to Fig. 1 it will be noted that a fibre body 11, to which has been secured a metal closed end 12, is provided in the present instance in the flattened form frequently given tobacco boxes. The label ⁶⁵ is preferably affixed to this body before the cover is applied as will be now described. This body is adapted to be slipped over a hinge or mandrel 13, a tongue or shim 14 being provided to extend above the upper ⁷⁰ flat wall of the box body as it goes on to the mandrel. A staple 15, having a main central part 16 and two legs 17, is then brought down to embrace the tongue 14 and is forced through the fibre body by a ⁷⁵ bumper 18 which completely positions the staple bending its legs 17 into clinched relation with the inside of the body. The tongue or shim 14 holds the body or main part 16 of the staple away from the box ⁸⁰ body as is indicated in Fig. 4.

Referring now to Fig. 5, it will be noted that a cover 21 is provided, having a peripheral flange 22 from which extends out a hinged lip or tongue 23. This tongue is ⁸⁵ inserted beneath the staple as indicated in Fig. 5 and is thereafter bent to embrace the body 16 of the staple. This may be accomplished as shown in Fig. 6. A staple tool or instrument 24 is used to push the tongue ⁹⁰ back into the position shown in Fig. 6 and the tongue is then bumped by a bumper 25 to clinch it about the part 16.

The staple is thus completely positioned before the cover is brought to assembling ⁹⁵ relation and it will be noted that the legs of the staple produce the perforations through which they extend into clinching position.

The hinge is thus formed without in any ¹⁰⁰ way damaging or weakening the paper or fiber material of the box body, and also without marring or scarring a label previously applied. The ends of the staple need not be imbedded in it and the material need ¹⁰⁵ not be offset to accommodate the staple. The hinge action of the box remains free, and when the open end of the fiber body is pressed in to permit the cover to close, a strong tight engagement results. ¹¹⁰

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I do not claim herein the article or box produced by this process and apparatus, the same being the subject of my application which is a division hereof, filed July 7, 1919.

15. I claim:

1. The process of manufacturing containers, which comprises first providing a body, then inserting a staple through the body, spacing the staple at its ends away from the main body of the container and clinching its ends and then inserting the hinged lip of a cover between the body of said staple and the body of a container.

2. The process of constructing containers, which consists in providing the completed body of a container, attaching thereto a hinge-staple, holding the hinge element away from the body of the container by means which are removable to permit the introduction of the cover portion of the hinge, and then introducing the hinge element of the cover under the hinge element of the staple and completing the formation of the hinge between the body and cover.

35. 3. The process of constructing a container,

which consists in providing a container body, positioning a staple and clinching the ends while holding the body of the staple away from a container body by means which are removable to permit the introduction 40 of the hinge element of the cover, and subsequently securing the cover to said staple.

4. The process of manufacturing containers, which consists in providing a fibre body, inserting a hinge-staple in place by forcing 45 the ends or legs of the staple to perforate the body while the body of the staple is held away from the said body of the container, and subsequently securing the cover by inserting a hinge element of the cover under 50 the staple.

5. The process of manufacturing containers, which comprises first making the container body, then applying a label thereto and subsequently attaching the hinge of a 55 hinged cover by a staple taking through the label and into the container body.

6. In an apparatus for making boxes, the combination of a mandrel on which the box body may be positioned, a shim adapted to be embraced by a staple to hold the body of the staple away from the box body, means for pressing upon the staple embracing said shim to clinch the ends of the staple within said body, and means for bending a hinged 60 tongue of a cover about said staple when the hinged tongue has been disposed through the space provided by the shim.

HARRY W. JONES.
